UNITED STATES PATENT OFFICE.

ERNEST N. HUMPHREY, OF NEW BRITAIN, CONNECTICUT, ASSIGNOR TO THE TRAUT & HINE MANUFACTURING COMPANY, OF NEW BRITAIN, CONNECTICUT, A CORPORATION OF CONNECTICUT.

BUCKLE.

1,161,804.

Specification of Letters Patent. Patented Nov. 23, 1915.

Application filed November 11, 1914. Serial No. 871,435.

To all whom it may concern:

Be it known that I, ERNEST N. HUMPHREY, a citizen of the United States, residing at the city of New Britain, county of 5 Hartford, State of Connecticut, have invented certain new and useful Improvements in Buckles, of which the following is a full, clear, and exact description.

My invention relates to garment 10 supporter trimmings and particularly to an improved buckle for use therewith.

In the drawings,—Figure 1 is a front elevation of said buckle. Fig. 2 is a horizontal section on the line 2—2. Fig. 3 is a vertical section on the line 3—3. Fig. 4 is a perspective view of the buckle-frame. Fig. 5 is a perspective view of the gripping-lever.

The buckle comprises two parts,—namely a frame and a web-gripping lever pivoted on 20 the frame and arranged to coöperate therewith to grip a piece of webbing. The frame comprises two bars 1 and 2, connected at their ends as at 3, 4. 5 represents a slot between said bars through which the webbing 25 passes. The bar 2 is of greater width than the bar 1 and is provided near each end with oppositely arranged L-shaped slots 6, 7, the outer ends of each of said slots extending into the slot 5, near the ends of the latter.

30 By this arrangement the edge 2^a of the bar is made flexible, the degree of flexibility being determined by the length of the said L-shaped slots 6, 7. The bar 1 is somewhat offset from the plane of the bar 2, so as to 35 be projected forwardly of said plane, as best seen in Fig. 3. The lever comprises the exposed arm 8, the gripping part 9 and the knuckle portions 10, 10, the latter being formed at each end of the lever, the gripping part 9 being of a length substantially 40 equal to the length of the yielding edge 2^a of the bar 2. 11 represents a piece of webbing, one end of which is looped around the bar 2 and over the yielding edge 2^a, said 45 looped end being stitched as at 12, or otherwise suitably fastened. The other end of the webbing runs through the space between the loop in the first-mentioned end of the webbing and the gripping part 9 of the le-

ver. Assuming that the lever is cast off or 50 opened so as to disengage the gripping part 9 from the webbing, the latter may be freely pulled through to the desired position, whereupon the lever may be closed down so as to frictionally engage the webbing. As 55 the lever is closed down, the yielding edge 2^a of the bar 2 will yield and allow the lever to snap past and to assume the position shown in Fig. 3, wherein the parts will be effectively held in operative position. 60

It will be observed that a substantial advantage is gained by providing the L-shaped slots described, in that the gripping edge 2^a may be unbroken throughout its length, which corresponds nearly to the over-all 65 width of the webbing, thus affording a maximum total pressure upon the webbing throughout substantially its entire width, with a minimum of unit or point pressure thereon, this arrangement adding materially 70 to the durability of the webbing and the effectiveness of the buckle.

It is obvious that the degree of flexibility of the yielding edge 2^a may be varied by 75 simply varying the length of the L-shaped slots, and this may be done without in any manner cutting into, or otherwise injuring, the relatively long and uninterrupted yielding edge 2^a, upon which the webbing is supported at all times. 80

What I claim is:

In a buckle, a one-piece sheet metal frame comprising continuous top and bottom bars connected at their ends in spaced apart relation to provide a web passage between 85 them, a gripping lever pivoted on the top bar, said bottom bar having oppositely arranged L-shaped slots formed therein extending from the central portion of said bar toward the ends of the bar and thence angularly to the web passage between the bars to thereby provide the bottom bar with a continuous relatively yielding edge forming the lower edge of the web passage. 90

ERNEST N. HUMPHREY.
